UNITED STATES PATENT OFFICE.

HARRY TUNSTALL, OF FAIR HAVEN, MASSACHUSETTS, ASSIGNOR TO ALSATIAN MACHINE WORKS, LIMITED, OF BOSTON, MASSACHUSETTS, A CORPORATION OF MASSACHUSETTS.

DRAWING FRAME.

Application filed November 14, 1923. Serial No. 674,708.

In Letters Patent No. 1,351,076, issued to me, I have shown and described a combing machine in which the comb cylinders are given a regular constant rotation, but I have found by experience that it is very desirable that the speed of rotation of the comb cylinder shall be variable, the more rapid part of its rotation being at a time when its clothing or teeth are passing under the rear detaching roll. When the last row of teeth have passed the detaching roll the speed of the cylinder should be slower until the first row of teeth again reach the detaching roll. I have shown and shall describe my improvement in connection with a double comber like that described in my said patent, but it will be evident to anyone skilled in the art that its improved features are equally applicable to a single comber or to other machines where such changes of speed are desirable.

My invention will be understood by reference to the drawings in which it is shown in its preferred form.

Figure 1 is an elevation of one of the supporting frames of a machine embodying my invention in its preferred form, corresponding to Fig. 5 of my said patent.

Fig. 2 is a side elevation of a portion of such a machine including the frame shown in Fig. 1 and certain of the frames shown in Figs. 2 and 2^a of my said patent, the intermediate portions comprising the nipper frames, etc. being broken away.

Fig. 3 is a plan view similar to Fig. 2, and

Fig. 4 is a detail to be described below.

A, A¹ are vertical members of the frame. The power shaft 1 is mounted as in said patent and carries a pinion 3 which engages the gear 31 on the shaft 8. On the shaft 8 is also a smaller gear 7 in mesh with a gear 2 on stud 21, which gear 2 is in mesh with a gear 6 which in turn is in mesh with a gear 61. Gears 6 and 61 are each on jack shafts 6^a and 61^a. Each of these jack shafts 6^a and 61^a carries an elliptical gear 62 and 62^a and each of these elliptical gears is in mesh with a similar elliptical gear 64 and 64^a on the shafts 63, 63^a, respectively, corresponding to the shafts 63 of my said patent. These two pairs of elliptical gears 62 and 64 and 62^a and 64^a are arranged in opposite relation to each other on their respective shafts so that the gears of each pair are

always in mesh. The elliptical gear 62^a is the driving gear of the system.

The gears referred to as elliptical gears are in fact elliptical, each having a long and short axis varying the fraction of an inch in length so that their difference cannot be distinguished in the drawing. They are also set eccentrically on their shafts. This description also applies to elliptical gears 631 and 631^a referred to below.

As in my said patent, the comb cylinders are mounted on these shafts 63, 63^a and by the use of elliptical gears arranged as shown power applied to the gear 6 from shaft 1 will turn the shafts 63, 63^a and the comb cylinders will be given rotation at variable speeds, one of the combs being given its rapid rotation while the other is moving more slowly. It will also be seen from my said patent that in the machine's operation while the nipper frames on one side of the machine are active, that is, are carrying the fleece to the detaching rolls, at the same moment the nipper frames on the other side of the machine will have dropped the fleece (see Fig. 3 of said patent). It is while the nippers are active that rapid movement should be given to the cylinder combs in this machine.

It is also necessary, however, in machines of this class that the draw box and cans, which are to receive the comber fleece or sliver, should be moved in a regular, not variable manner. In machines embodying the invention of my said patent, the draw box and cans are located in front of the end of the machine (see Fig. 1 of said patent where the shafts 63 are shown in section indicating that the shafts 63 are extended for this purpose). To translate the variable movement given to the shafts 63, 63^a so as to give a regular movement to the draw box and cans, I provide on the farther end of the driving shaft 63^a of the elliptical gear system described, an elliptical gear 631^a which is set with its long diameter at 180 degrees to the long diameter of the gear 64^a at the other end of the shaft. 641 is a sleeve mounted in the support A about the shaft 63 and movable independently thereof. This sleeve carries a second elliptical gear 631 together with a bevel gear 65 in mesh with the bevel gear 66 on the draw box operating shaft 67. The draw boxes are mounted on brackets A², A² carried by the

frame A¹ and are not shown as they may be of any well known construction. They carry gears which mesh with the gears 69 on shaft 67. This shaft also carries gears 68 which mesh with the usual can driving mechanism.

It will be seen that the gear 6 which is rotated at a constant speed gives a variable speed through elliptical gears 62^a and 64^a 10 to the shaft 63^a and through the gear 61 to the elliptical gears 62 and 64 and the shaft 63. This variable speed is translated into constant speed by the elliptical gear 63^a 15 engaging the elliptical gear 631 on sleeve 641 which is given a constant speed and rotates the bevel gears 65 and 66 and the shaft 67 and its gears 68 and 69.

My invention may be utilized in other machines where it is desired to secure a variable 20 from a constant speed and to translate said variable speed into a constant speed again, and it is evident that in its details the construction shown may be varied without departing from the inventive idea above described. It is also evident that additional results may be accomplished by changing the relative sizes of the various gears or by increasing the number thereof.

It is also evident that the sleeve 641 being 25 independent of the shaft 63, that is, being formed to rotate about it, may be a solid shaft.

I have shown the mounting for the elliptical gear 631 as a sleeve 641 on shaft 63, but 30 this is merely a convenient way of supporting the gear 631 in the frame A in such manner that it will rotate independently of the shaft 63, and in using the word "sleeve" in my claims I do not mean to limit myself 40 to a hollow shaft mounted to turn on shaft 63, but to include any suitable means for supporting the gear 631 so that it may be

freely turned by the shaft 63^a to give proper constant speed to the drawing frame mechanism.

It will be noted that in the drawing the elliptical gears are all shown as mounted eccentrically on their respective shafts. This construction has been found very desirable, being a refinement of mounting which seems to be rendered necessary because of the material on which a combing machine works,—a material comprising laps of minute fibres which are combed by the machine.

What I claim as my invention is:—

1. In a combing machine, a combing cylinder shaft having an elliptical gear at each end, a power shaft also having an elliptical gear in mesh with one of said first-named elliptical gears whereby power is applied to rotate said combing cylinder and a fourth elliptical gear in mesh with the other elliptical gear on said combing cylinder shaft, said last-named elliptical gear carrying a bevel gear, and a draw box shaft also carrying a bevel gear.

2. In a combing machine, two parallel combing cylinders, each having a driving elliptical gear at one end, said gears being in mesh, means for driving it whereby said combing cylinders will be given a variable rotation, one of said combing cylinder shafts also carrying an eccentric gear at its further end in combination with a fourth eccentric gear independently mounted and carrying a bevel gear and a draw box shaft having a bevel gear thereon in mesh with said first-named bevel gear whereby the variable rotation of said combing cylinder shaft will communicate a constant rotation to said draw box shaft.

HARRY TUNSTALL.
